SWITCH

Robert H. Hill, Anderson, Ind., assignor to General Motors Corporation, Detroit, Mich., a corporation of Delaware

Application July 22, 1937, Serial No. 154,958

11 Claims. (Cl. 200—76)

This invention relates to switches, and more particularly to the push button type, capable of handling heavy currents, such as are employed in the primary starting motor circuit for busses or trucks.

An object of the present invention is to provide a switch construction which offers a quick-make and a quick-break action.

Another object is to provide a switch structure of the snap action character that is compact in form and which may be easily assembled and manufactured.

Another object of the invention is to provide a switch, in which the movable contact assembly is of the floating type, with means for effecting good pressure contact between the contact elements during the period the circuit is closed and which provides for the greatest pressure contact just before the circuit is broken.

Another object of the present invention is to provide a push button switch construction with means to actuate the movable contact, in which the movable contact is beyond the control of the operator after the button has been depressed beyond a certain predetermined point.

Another object is to provide a push button switch construction for starting motor circuits which is comparatively easy to hold in a circuit closed position and which permits the push button to move in a return direction a certain distance, without affecting the contact pressure.

Further objects and advantages of the present invention will be apparent from the following description, reference being had to the accompanying drawings wherein a preferred embodiment of the present invention is clearly shown.

In the drawings:

Fig. 1 is a view in elevation of the switch.

Fig. 2 is an enlarged sectional view of the switch with the controlling parts shown in normal or inoperative positions.

Fig. 3 is a sectional view taken on the line 3—3 of Fig. 2.

Fig. 4 is a sectional view taken on the line 4—4 of Fig. 5.

Fig. 5 is a sectional view of the switch showing the actuator or push button depressed and the contacts of the switch in closed position.

Fig. 6 is an elevational view, partly in section, showing a modification of a movable contact assembly in elevation.

Fig. 7 is a sectional view of the contact assembly shown in Fig. 6 and taken on the line 7—7 of Fig. 6.

Fig. 8 is a sectional view taken on the line 8—8 of Fig. 7.

Referring to the drawings, the switch structure embodying the present invention comprises a metallic cup-shaped housing 20 having a bottom wall 21 provided with an opening 22 to receive a collar or sleeve 23. The sleeve is rigidly secured to the wall in any suitable manner. In the present instance the sleeve is provided with a reduced portion projecting through the opening 22 and spun over, as at 24, against the under surface of the wall 21.

The sleeve 23 slidably supports a push-button 25 of insulating material. The button is provided with an annular recess 26 to form a hub portion 27. The hub portion supports a rod or actuator 28, substantially concentric with the sleeve 23, and extends into the housing 20. This rod is formed with a cylindrical portion 29, an intermediate cam portion which includes inclined surfaces 31, 32 and 33, and a cylindrical end portion 34. The inclined portion 32 is preferably a little steeper than the surface 33. The intermediate cam portion is so arranged that the base of the inclined surface 31 cooperates with the cylindrical portion 29 to form a shoulder 35 on the actuator. The inclined surfaces 31 and 32 are arranged to form a channel 36 and the inclined surfaces 32 and 33 meet to form a ridge 37.

A coiled spring 40 surrounds the rod 28 and has one end seated in the recess 26 while the other end rests on a washer 41 which rests upon a stop washer 42 made of non-conducting material. The washer 42 is provided with a slot 43 which terminates into a central opening. This opening forms a guide or bearing for the cylindrical portion 29 of the rod 28. The washer 42 is preferably held against the bottom wall of the housing by the cooperation of a spacer washer 44, a removable terminal assembly 45, an insulating sleeve 46 and a closure 47. In the present instance the washer 44 is formed with a central opening 48 of greater dimensions than the base of the inclined portion 31 to permit same to pass therethrough and normally rest on the washer 42 which limits the outward movement of the rod 28. The washer 42 is also provided with radial slots 49 extending from the boundary of the opening 48. These notches receive the head of the rivets 50 on the removable terminal assembly 45.

The terminal assembly 45 comprises a disc 51 of non-conducting material having a central opening 52 in alignment with the opening 48 of the washer 44. The washer 51 is provided with notches 53 extending from the boundary of the

opening 52 to receive tangs 54 formed integral with the terminals 55, 56 and a "dummy" plate 57 to prevent the terminals and the plate from turning relative to the disc 51. The terminals and the plate are provided with notches 58 and 58a respectively to receive tongues 59 of similarly formed resilient blades 60. These blades are preferably arcuate in formation. A blade 60 is secured to each terminal and the dummy plate 10 by rivets having the head 50 which project into the slots 49 of the disc 44. The terminals 55 and 56 are provided with projections 55a and 56a, respectively, which project beyond the housing. These projections are received by suitable apertures 62 provided in the closure 47. By this arrangement the terminal ends 55a and 56a are held free of the metal housing 20.

The closure 47 centrally supports a stop or cup member 65 and is rigidly secured thereto by a sleeve 66. The sleeve is provided with a flange 67 which engages the bottom wall of the cup and a reduced portion. This reduced portion extends through a central aperture provided in the closure riveted over a metal washer 68. The sleeve 66 provides a guide for the cylindrical end 34 of the rod or actuator 28, and the stop-cup 65 limits the downward movement of a movable contact assembly 70.

A contact assembly 70, shown in Figs. 2, 3 and 5 comprises a body 71 of non-conducting material and is formed with a peripheral groove 72 with a transverse notch 73 formed therein, see Fig. 3. The groove 72 receives a resilient retainer band or snap ring 74 having a tongue 75. This tongue extends into the notch 73 to form an anchor for the band and prevents the band from rotating relative to the body 71. The body 71 has a central opening 76 which is slightly larger in dimensions than cross dimension of ridge 37 formed by the inclined surfaces 32 and 33 of the cam portion on the rod 20. A plurality of transverse passages 77 are formed in the body and each passage is adapted to receive a ball 78 and a coil spring 79. One end 45 of each spring rests on the band 74 and the other end engages a ball 78 to urge the ball against the actuator or rod 28. Preferably two annular contact bridging members 80 are secured to the body 71, one on each end of the body. These members are firmly held to the body by rivets 81, one of which is clearly shown in Fig. 1. One of the bridging members 80 is adapted to engage the contacts 82 and a dummy contact 82a which are attached to the free ends 55 of the resilient arcuate members 60 secured to the terminals 55, 56 and the plate 57. The purpose of the third contact 82a attached to the member 60 which in turn is secured to the plate 57, and which is shown in the present instance 60 constitutes a "dummy" contact, is to make a three point engagement for the contact assembly 45. By this arrangement the contact assembly 45 is prevented from rocking while in engagement with the contacts 82 and 82a. It is 65 to be understood that the third contact, namely the contact 82a and its associated plate 57, may be used to control an auxiliary circuit, if so desired.

The modified form of a movable contact assembly 85 is shown in Figs. 6, 7 and 8. This assembly comprises a bridging member 90 which houses a plurality of discs 91 and 92 of non-conducting material, each disc having a central opening slightly larger in dimension than the widened portion or ridge 37 of the cam portion

on the rod or actuator 28. The intermediate discs 92 are provided with oppositely disposed notches extending from the boundaries of the opening, which are covered by the discs 91 to provide recesses. Each recess receives a ball 78 and a spring 79. One end of each spring rests on the bottom of the recess and other end engages a ball to urge same against the actuator extending through the assembly.

To assemble the movable contact assembly 85, the bridging member 90 is first formed in cup-shaped formation as indicated by the dot and dash lines indicated in Fig. 8, then the discs 91 and 92, in the order shown, are placed into the cup. The end 90a is then spun over the 15 outer disc 91 to securely hold all of the discs in their desired positions.

In assembling the switch proper, the compression spring 40 is first positioned into the recess 26 of the button 25, then the washer 41 is placed 20 over the rod portion 29. The stop washer 42 is then fitted to the portion 29 whereby the spring 40 will urge the washer against the stop 35 on the rod 29. This assembly of parts is then inserted into the housing so that the button 25 25 projects beyond the sleeve 23 and the washer 42 engages the bottom wall 21 of the housing 20. Then the spacing washer 44 and either the terminal assembly 45 or the assembly 85 is inserted in the housing and over the actuator 30 followed by the sleeve 46, after which the closure 47 is slid over the terminal projection 55a and 56a until the cover 47 engages the outer edge of the housing. The closure 47 is provided with suitable peripheral notches 95 to receive tangs 96 formed integral with the housing 20, and bent over, to firmly secure the cover to the housing and hold the various elements in their normal position, as shown in Figs. 1 and 6.

When it is desired to operate the switch from the position shown in Fig. 1 to that shown in Fig. 5 to close a circuit, the operator depresses the button 25 causing the actuator 29 to move downwardly, as viewed in the drawings. As the actuator is moved downwardly the end 34 45 of the rod will be guided by the sleeve 66 and the balls 78 will be forced radially outward by the inclined surface 33 to compress the springs 79 to store up energy in the springs 79 until the balls rest on the ridge 37. When the actuator 50 has moved downwardly a predetermined distance so that the balls 78 pass the ridge 37 the springs 79 will then move the whole movable contact assembly with a snap action into engagement with the contacts 82 and 82a. The 55 movement of the contact assembly is beyond the control of the operator once the balls pass the ridge 37. When the balls 78 are past the ridge 37, the springs 79 will cause the balls to slide down on the inclined surface 32 and constantly 60 urge the contact assembly toward and against the contacts 82 and 82a, as indicated in Fig. 5, and place resilient members 60 under tension so as to provide a good contact pressure between the contacts. This arrangement also provides for a rubbing action between the contacts on slight movements of the contact assembly when same is in engagement with the contacts 82. This rubbing action between the contacts 70 will occur when the operator releases his hold slightly, while the switch is closed, as the contact assembly would move upwardly, as viewed in the drawings, by the spring 40 but the contacts would not be separated on slight movements to cause arcing or burning of the con-

tacts. Thus, by this arrangement it is practically impossible to burn the contacts due to either slow or fast movements of the operator in closing or opening the switch.

5. When it is desired to open the switch, the operator releases his hold on the button 25 and the switch is automatically opened by the spring 40. As the actuator is on the return movement the cam surface 32 urges the balls outward to compress the springs 79 until the balls reach the ridge 37. While the springs 79 are being compressed they also urge the balls 78 against the inclined surface 32 tending to urge the contact assembly toward the contacts 82 and 82a thus constantly increasing the pressure contact between same until the balls reach the apex formed by the inclined surfaces 31 and 32 at which time the contact pressure is at its maximum. The instant the balls are past the ridge 37 the contact assembly 45 or 90 is instantly moved with a snap action to separate the contacts to an open position thus preventing arcing or burning of the contacts.

An important advantage resulting from this or other arrangements embodying this invention is that it decreases to a minimum the replacement of switches used for the primary starting circuit for busses and trucks wherein a relative high amperage and high voltage is required normally about 20 amperes at 24 volts.

While the embodiment of the present invention as herein disclosed, constitutes a preferred form, it is to be understood that other forms might be adopted, all coming within the scope 35 of the claims which follow.

What is claimed is as follows:

1. An electric switch comprising, in combination; a cup-shaped housing; a unitary stationary contact assembly comprising an insulating plate, terminals carried by the plate, said terminals comprising a flexible contact portion and a rigid portion secured to the plate with the rigid portion continuing beyond the open end of the housing; an insulating sleeve; a closure for the housing having recesses to receive the rigid portions, said sleeve and closure cooperating to hold firmly the plate and the stationary contact assembly adjacent the bottom wall of the housing and insulating the rigid portion of the terminals 50 from the housing; a movable contact assembly including a contact carrier, a bridging member attached to the carrier; a manually operated actuator slidably supported by the plate and the closure; cam means carried by the actuator; and spring urged balls carried by the contact assembly and cooperating with the cam means to snap the contact into engagement with the flexible contacts on movement of the actuator in one direction and to snap the contact out of engagement from the flexible contacts on movement of the actuator in the opposite direction.

2. An electric switch, comprising in combination, a cup-shaped casing; a removable block of non-conducting material located within the casing; terminal contacts carried by the block and having portions projecting beyond the open end of the casing; a sleeve of non-conducting material; a closure for the housing having openings to receive the projecting portions and also co-operating with the sleeve to hold firmly the block adjacent the bottom wall of the casing and insulate the terminals from the housing; and a contact axially movable with a snap action into and out of contact with the terminals.

3. An electric switch comprising in combina-

tion; a cup-shaped housing; a terminal support assembly removably supported within the housing comprising an insulating disc; terminals secured to the disc and having projections adapted to extend beyond the open end of the housing; resilient contact members greater in number than the terminals; secured to the disc and the terminals, said contact members being arranged in a circular row to provide for an equal pressure at all points for a movable contact movable within the housing to prevent rocking thereof; a non-conducting sleeve about the terminals; a closure for the housing provided with openings to receive the projections of the terminals, said closure cooperating with the sleeve to hold the terminal assembly against the bottom wall of the housing; and means for securing the closure to the housing.

4. An electric switch comprising in combination; a terminal support assembly including resilient members providing contact engaging portions equally spaced to provide for a three point engagement for a movable contact to prevent rocking of the movable contact; an actuator for the movable contact; and coacting means carried by the actuator and the movable contact to snap the movable contact into engagement with the resilient members to close an electric circuit, and said coacting means also operating to place the resilient members under tension whereby a full pressure contact between the resilient members and the movable contact is obtained up to the time of separation.

5. An electric switch comprising in combination; a housing; an insulating disc; a removable terminal support; an insulating sleeve; a closure for the housing cooperating with the sleeve for holding the disc and support in a definite position within the housing; a movable contact assembly within the housing; a manually operated actuator mounted for straight-line movements and projecting through the movable contact assembly, said actuator provided with means on each side of the disc, said means cooperating with the disc to limit the movements of the actuator in either direction; coacting means carried by the actuator and the movable contact assembly to snap the movable contact assembly into and out of engagement with the terminals; and resilient means adapted for urging the actuator in one direction of its straight-line movement when the actuator is manually operated in another direction and released.

6. An electric switch comprising in combination; a cup-shaped housing; an insulating plate; a removable terminal support the terminals having portions extending beyond the open end of the housing; an insulating member; a closure for the housing having openings to receive the extending portions of the terminals and cooperating with the member to hold the terminal support and plate against the bottom wall of the housing; a movable contact assembly within the housing; a manually actuated plunger mounted for straight-line movements and extending through the movable contact assembly and provided with stop portions on each side of the plate, the stop portions cooperating with the plate to limit the movement of the plunger in either direction; coacting means carried by the plunger and the movable contact assembly to snap the assembly into engagement with the terminals upon manual movement of the plunger in one direction; and spring means for moving the plunger in the opposite direction upon release of the manual

actuated means causing the assembly to be snap actuated out of engagement from the terminals.

7. A movable contact assembly for a switching mechanism comprising in combination; a body of insulating material formed with an axial bore to receive an actuator and having a plurality of radial bores communicating with the axial bore; a ball and a spring located in each radial bore; a retainer ring about the periphery of the body for closing one end of the radial bores, said ring forming a seat for one end of the springs whereby the springs will urge the balls against the actuator; and a bridging member applied to the faces of the body to expose a portion of the body between the actuator and the bridging member.

8. A movable contact assembly for a switching mechanism comprising in combination, a body of non-conducting material formed with a peripheral groove provided with a recess and having an axial bore to receive an actuator and having a plurality of radial bores communicating with the axial bore and the groove; a ball and a spring located with each radial bore; a band located in the groove and extending over the radial bores to form seals for one end of the spring whereby the springs will urge the balls toward the actuator, one end of the band being anchored in the recess to prevent rotary movement of the band relative to the body; and bridging members supplied to the faces of the body to expose a portion of the body between actuator and the bridging member.

9. An electric switch comprising in combination; a metallic cup-shaped housing; a removable terminal support assembly located within the housing comprising terminals provided with contact portion and having projections adapted to extend beyond the open end of the housing; an insulating member for lining the interior wall of the housing and to insulate the terminal pro-

jections from the housing; a closure for the housing, said closure cooperating with the insulating member to hold firmly the terminal support assembly against the closed end of the housing; an actuator carrying cam means; and a movable contact slideable on the actuator and carry spring urged balls cooperating with the cam means of the actuator whereby the movable contact will be snap actuated into and out of engagement with the terminal contact portions upon actuation of the actuator.

10. A movable contact assembly comprising in combination; a plurality of superposed discs of insulating material, each disc having a through opening to surround an actuator with the intermediate disc having a recess extending from its opening to receive spring urged means adapted to engage the actuator; and a bridging member for holding the discs together, said bridging member comprising a cup-shaped member having an apertured bottom wall through which the actuator may extend and against which the lowermost disc rests and having the open end bent inwardly over the uppermost disc.

11. An electric switch, comprising in combination, a cup-shaped housing; a removable block located within the housing; terminal contacts carried by the block and having portions projecting outside the housing; a sleeve of insulating material; a closure for the housing, said closure cooperating with the sleeve to hold firmly the block against the bottom wall of the housing and to insulate the terminals from the housing; a movable contact normally out of engagement with the terminals; and means extending through the movable contact and operable for actuating the movable contact with a snap action into and out of engagement with the terminals.

ROBERT H. HILL. 40
